(57) **CLAIM**

The ornamental design for a roundabout for children's playgrounds, as shown and described.

DESCRIPTION

1. Roundabout for children's playgrounds

1.1 : Perspective

1.2 : Front

1.3 : Back

1.4 : Left

1.5 : Top

1.6 : Bottom

Design 1 shows a new roundabout for children's playgrounds; the features shown in dashed lines in the drawings depict environmental subject matter only, and form no part of the claimed designs; left and right views are identical.
